UNITED STATES PATENT OFFICE.

ERNEST WILLIAM MARSH, OF RAWDON, NEAR LEEDS, ENGLAND.

SCRAPER MECHANISM FOR REMOVING THE BURRS FROM THE TROUGHES OR BURR TINS OF CARDING ENGINES.

Application filed October 8, 1924. Serial No. 742,442.

To all whom it may concern:

Be it known that I, ERNEST WILLIAM MARSH, a British subject, residing at Rawdon, near Leeds, in the county of York, England, have invented an Improved Scraper Mechanism for Removing the Burrs from the Troughs or Burr Tins of Carding Engines, of which the following is a specification.

19 This invention has for its object the provision of a new or improved scraper-mechanism, as hereinafter described, for removing the burrs from the troughs or burr tins of carding-engines, which is more efficient than 15 the scraper-mechanisms hitherto proposed or used for this purpose.

According to my invention, the scraper-mechanism comprises a slidably and pivotally mounted scraper blade which is travelled across the machine in one direction so as to remove the collected burrs from the trough or burr tin, then lifted into an up position and travelled across the machine in the opposite direction, and then lowered 25 or let fall into the down position for the subsequent burr-removing traverse.

In order that the invention may be clearly understood, I will proceed to describe the same with reference to the example of construction shown in the accompanying drawings; wherein:—

30 Figs. 1 and 2 are respectively a part sectional front elevation and a sectional side elevation of my improved scraper-mechanism applied to a burr tin of a carding engine.

35 Referring to the drawings, the side frames 1 of the carding engine are provided with upstanding brackets 2 to which the burr tin 3 is attached, and the brackets 2 carry a fixed transverse rod 4 upon which is slidably and pivotally mounted an arm 5 formed on its underside with a tooth 6 which at times engages the thread of a transverse screwed 40 shaft 7 and on its upperside with a tooth 8 which at other times engages the thread of a transverse screwed shaft 9, while to the outer or free end of the said arm 5 is fixed a scraper blade 10. The transverse screwed shafts 7, 9 are carried by the brackets 2 and are geared together by a pair of spur wheels 11, while the brackets 2 carry a fixed transverse slide bar 12 with which projections 13, 14 formed on the blade-carrying arm 5 alternately engage so as to support the latter

when meshed with the transverse screwed shafts 9, 7 respectively; a cam 15 formed on the transverse screwed shaft 7 being provided for lifting the blade-carrying arm 5 out of mesh with the transverse screwed shaft 60 7 and into mesh with the transverse screwed shaft 9.

The transverse screwed shaft 7 is driven in the direction indicated by an arrow (Fig. 2) through suitable means (not shown) and imparts a reverse rotary motion to the transverse screwed shaft 9 through the medium of the geared spur wheels 11 and assuming the parts to be in the position shown at Fig. 1 and in full lines at Fig. 2, the blade-carrying arm 5 is, through the medium of its meshed tooth 6, travelled along its transverse rod 4 by the transverse screwed shaft 7 until the said arm 5 rides on to the cam 15, whereupon the latter automatically lifts the said blade-carrying arm 5 so as to cause its projection 13 to pass through a notch 16 in the transverse slide bar 12 and bring the tooth 8 into mesh with the thread of the screwed shaft 9 as shown in dotted lines at Fig. 2, after which the transverse screwed shaft 9 travels the blade-carrying arm 5 along its transverse rod 4 with the supporting projection 13 behind the transverse slide bar 12. On the blade-carrying arm 5 arriving at the opposite end of its transverse rod 4, the projection 13 passes through a notch 17 in the transverse slide bar 12 and the blade-carrying arm 5 falls so as to bring its tooth 6 into mesh with the thread of the 85 90 screwed shaft 7 and cause the projection 14 to engage behind the transverse slide bar 12 and support the said arm 5 as shown in full lines at Fig. 2, whereupon the blade-carrying arm 5 is travelled along its transverse 95 rod 4 by the said transverse screwed shaft 7 until it again arrives at the lifting cam 15, after which the above cycle of operations is continuously repeated.

It will thus be seen that the arm 5 is travelled across the machine in one direction by the transverse screwed shaft 7 so as to cause the scraper blade 10 to remove the collected burrs from the burr tin 3, then lifted by the cam 15 and travelled across the machine in the opposite direction by the transverse screwed shaft 9, and then let fall into the down position for the subsequent burr-removing traverse.

The pitch of the screws on the transverse 110

screwed shafts 7, 9 and the gear ratio of the spur wheels 11 are such as to give the blade-carrying arm 5 a slow burr-removing traverse and a fast return traverse.

5. What I claim as my invention and desire to secure by Letters Patent is:—

1. A scraper-mechanism for removing the burrs from the troughs or burr tins of carding engines, comprising a slidably and pivotingally mounted scraper blade, a rotating transverse screwed shaft for effecting the burr-removing traverse of the scraper blade, a second rotating transverse screwed shaft for effecting the return traverse of the scraper blade, means for transferring the scraper blade from one screwed shaft to the other at the end of its burr-removing traverse, and means for transferring it from one screwed shaft to the other at the end of its return traverse.

2. A scraper-mechanism for removing the burrs from the troughs or burr tins of carding engines, comprising a scraper blade, a transverse rod, an arm slidably and pivotingally mounted on said transverse rod, and by which the scraper blade is carried, a rotating transverse screwed shaft for travelling the blade-carrying arm across the machine in one direction so as to remove the collected burrs from the burr tins, means for lifting the blade-carrying arm into an up position after its burr removing traverse, a second rotating transverse screwed shaft for travelling the blade-carrying arm across the machine in the opposite direction, and means for letting the blade-carrying arm fall into the down position for the subsequent burr-removing traverse.

3. A scraper-mechanism for removing the burrs from the troughs or burr tins of carding engines, comprising a scraper blade, a fixed transverse rod, an arm slidably and pivotally mounted on said transverse rod, and by which the said scraper blade is carried, a rotating transverse screwed shaft for travelling the blade-carrying arm across the machine in one direction so as to remove the collected burrs from the burr tins, a cam on said rotating transverse screwed shaft for lifting the blade-carrying arm into an up position after its burr removing traverse, a second rotating transverse screwed shaft for travelling the blade-carrying arm across the machine in the opposite direction, and means for letting the blade-carrying arm fall into the down position for the subsequent burr-removing traverse.

4. A scraper-mechanism for removing the burrs from the troughs or burr tins of carding engines, comprising a scraper blade, a fixed transverse rod, an arm slidably and pivotally mounted on said fixed transverse rod, and by which said scraper blade is carried, a rotating transverse screwed shaft, a

tooth on the under side of the blade-carrying arm adapted to mesh with the said rotating transverse screwed shaft, by which the said blade-carrying arm is travelled across the machine in one direction so as to remove the collected burrs from the burr tin, a tooth on the upper side of the said blade-carrying arm, a second rotating transverse screwed shaft, a cam on the first rotating transverse screwed shaft for lifting the blade-carrying arm into an up position after its burr removing traverse to bring the tooth on the upper side of the said blade-carrying arm into mesh with the said second rotating transverse screwed shaft, by which the said blade-carrying arm is travelled across the machine in the opposite direction, and means for letting the blade-carrying arm fall into the down position for the subsequent burr-removing traverse.

5. A scraper-mechanism for removing the burrs from the troughs or burr tins of carding engines, comprising a scraper blade, a fixed transverse rod, an arm slidably and pivotally mounted on said fixed transverse rod, and by which the said scraper blade is carried, a rotating transverse screwed shaft, a tooth on the under side of the blade-carrying arm adapted to mesh with the thread of the said rotating transverse screwed shaft, by which the said blade-carrying arm is travelled across the machine in one direction so as to remove the collected burrs from the burr tin, a tooth on the upper side of the said blade-carrying arm, a second rotating transverse screwed shaft, a cam on the first rotating transverse screwed shaft for lifting the blade-carrying arm into an up position after its burr removing traverse, to bring the said tooth on the upper side of the said blade-carrying arm into mesh with the thread of the said second rotating transverse screwed shaft, by which the said blade-carrying arm is travelled across the machine in the opposite direction, means for supporting the blade-carrying arm during both directions of its traverse across the machine, and means for letting the blade-carrying arm fall into the down position for the subsequent burr-removing traverse.

6. A scraper-mechanism for removing the burrs from the troughs or burr tins of carding engines, comprising a scraper blade, a fixed transverse rod, an arm slidably and pivotally mounted on said fixed transverse rod, and by which the said scraper blade is carried, a rotating transverse screwed shaft, a tooth on the under side of the blade-carrying arm adapted to mesh with the thread of the said rotating transverse screwed shaft, by which the said blade-carrying arm is travelled across the machine in one direction so as to remove the collected burrs from the burr tin, a tooth on the upper side of the said blade-carrying arm, a second rotating

transverse screwed shaft, a cam on the first aforesaid rotating transverse screwed shaft for lifting the blade-carrying arm into an up position after its burr-removing traverse 5 to bring the said tooth on the upper side of the blade-carrying arm into mesh with the thread of the said second rotating transverse screwed shaft, by which the blade-carrying arm is travelled across the machine in the 10 opposite direction, a fixed transverse slide bar, projections on the said blade-carrying arm which alternately engage behind the said fixed transverse slide bar for supporting the blade-carrying arm during both directions of its traverse across the machine, and means for letting the blade-carrying arm fall into the down position for the subsequent burr-removing traverse.

7. A scraper mechanism for removing the burrs from the troughs or burr tins of carding engines, comprising a scraper blade, a fixed transverse rod, an arm slidably and pivotally mounted on the said fixed transverse rod, and by which the scraper blade is carried, a rotating transverse screwed shaft, a tooth on the under side of the said blade-carrying arm adapted to mesh with the thread of the said rotating transverse screwed shaft, by which the said blade-car-

rying arm is travelled across the machine 30 in one direction so as to remove the collected burrs from the burr tin, a tooth on the upper side of the said blade-carrying arm, a second rotating transverse screwed shaft, a cam on the first aforesaid rotating transverse 35 screwed shaft for lifting the blade-carrying arm into an up position after its burr-removing traverse to bring the said tooth on the upper side of the blade-carrying arm into mesh with the thread of the said second rotating transverse screwed shaft, by which the said blade-carrying arm is travelled across the machine in the opposite direction, a fixed transverse slide bar, and projections on the said blade-carrying arm, which alternately engage behind the said fixed transverse slide bar for supporting the blade-carrying arm during both directions of its traverse across the machine, there being a notch in the said fixed transverse slide bar 50 for freeing the engaging projection of the blade-carrying arm so as to permit the latter to fall into the down position for the subsequent burr-removing traverse.

In witness whereof I have hereunto set 55 my hand.

ERNEST WILLIAM MARSH.
